UNITED STATES PATENT OFFICE.

SAMUEL E. MORRAL AND WILLIAM W. MORRAL, OF MORRAL, OHIO.

CORN-HUSKING MACHINE.

1,372,767.

Specification of Letters Patent. Patented Mar. 29, 1921.

Application filed January 2, 1919. Serial No. 269,236.

To all whom it may concern:

Be it known that we, SAMUEL E. MORRAL and WILLIAM W. MORRAL, citizens of the United States, residing at Morral, in the 5 county of Marion and State of Ohio, have invented certain new and useful Improvements in Corn-Husking Machines, of which the following is a specification, reference being had therein to the accompanying drawing.

10 This invention relates to corn husking machines and is an improvement of the type of machine disclosed in Patent No. 1,121,937, issued to us December 22, 1914.

15 The object of the invention is to provide improved husking rollers adapted for use in machines of the type disclosed in the above cited patent and which may also be used in other types of corn husking machines by 20 making suitable modifications of the general construction and arrangement of the improved rollers, however, without departing from the principle of the invention.

25 The particular novelty of our improved husking rollers consists in associating or combining a roller having a plain surface with a roller provided with a spiral groove extending substantially the entire length thereof at a suitable pitch and depth to provide for the removal of incidental obstructing matter, such as pieces of cob, husks or 30 foreign matter of any kind which would otherwise collect in the bite of the rollers and act to prevent the proper functioning 35 thereof.

The plain roller having the smooth surface may consist of a rubber covered shaft or, as shown in the drawings of the present construction, may be made entirely of metal.

40 The roller provided with the spiral groove is, of course, made of metal, the spirals being cut or formed therein in any suitable manner.

45 In the ordinary use of our improved rollers we have found that spirals approximately $\frac{1}{8}$ inch wide and $\frac{1}{8}$ inch deep and having about one inch pitch or lead give very satisfactory results. However, these dimensions may be varied to suit the conditions of 50 the material and the work.

The corn husking machine is disclosed and described in our issued patent above referred to and it will be necessary only there-

fore to illustrate and describe the particular parts of the machine with which the improved rollers are directly connected and operated.

In the disclosed form of application of the invention two sets of husking rollers are employed, one set rough husking rollers to which the ears of corn are first presented after the same have passed through the butting mechanism and which acts to tear loose the husks and remove the greater portion thereof, and a second set of finishing rollers which acts to remove any husks or silk remaining on the ears of corn after they have been operated on by the first set of rollers. The spiral grooves may be applied to one roller of each set or to one roller of one set only, as may be desired. In the preferred arrangement, however, one roller of each set is provided with the spiral groove.

Referring to the drawings, Figure 1 is a vertical longitudinal sectional view, taken through the upper portion of a machine, such as is disclosed in our patent above referred to and showing the position of the husking rollers therein;

Fig. 2 is a detail plan view of one pair of the husking rollers to which the present invention has been applied;

Fig. 3 is a detail plan view of the other pair of husking rollers to which the invention has been applied.

The husking machine is supported on a suitable main frame comprising side members 1 connected one to the other by transverse bars 2 having mounted thereon spacing sleeves 3 arranged between the side members 1. This main frame is supported by standards 4 which are secured to the respective side members 1 by means of the bars 2 and are mounted at their lower ends upon transversely extending supporting blocks or bases (not shown) which serve to tie together the legs of each pair, that is, the two legs at each end of the machine. The legs are further tied together by longitudinally extending side members which are bolted to the legs on the opposite sides of the machine.

Mechanism of a suitable character is preferably provided for removing the butts from the ears of corn. As shown in Fig. 1, this mechanism consists of a rotary cutter disk

5 mounted on a shaft 6 extending transversely to the main frame and journaled in bearings supported on the main frame. A suitable supporting table or bed plate 7 is
 5 arranged with an edge adjacent to the cutter and the ears of corn are fed over this table toward the cutter by suitable feeding mechanism which, in the present construction, comprises an endless carrier consisting of two
 10 sprocket chains 8 arranged on opposite sides of the supporting table and extending about sprocket wheels 9 carried by a shaft 10 journaled in the main frame and other sprocket wheels 11 mounted on a shaft 12 journaled in the frame at the other end of the supporting table. This feeding mechanism may be driven in any suitable manner, but preferably by an arrangement of chain and sprocket connections such as is shown
 15 in the patent referred to, the power being transmitted to the machine from any suitable source through a belt wheel 13.
 Suitable ear-engaging devices are secured to the sprocket chains at intervals arranged
 20 to extend above the supporting table and at substantially right angles to the line of movement of the ears of corn. Preferably, these devices are in the form of rollers 14 extending transversely between the sprocket
 25 chains and supported in any suitable manner to be carried forward over the supporting table with the travel of the chains. The rollers are supported at a distance above the chains to cause the same to engage the ears
 30 of corn at the proper distance above the table.

Means are provided for moving the ears of corn transversely to the supporting table and into a position to be engaged by the
 40 cutter disk 5. This means, as here shown, consists of a roller 15 extending longitudinally to the table and so arranged as to engage the upper surface of the ears and positively move the same toward that side of the
 45 supporting table adjacent to the cutter 5. The lateral movement of the ears is limited by guides which act to permit the tapered ends of the ears to pass between them, but engage the butts of the ears and thus check
 50 the lateral movement thereof. Suitable means, such as are disclosed in our patent referred to are provided for properly presenting the ears to the cutting mechanism, by means of which the butts are severed from
 55 the ears and the ears are then carried forward by the chain mechanism over the end of the machine and delivered to the first pair of husking rollers, as clearly shown in Fig. 1.

60 In the present construction, we have shown the corn husking mechanism as supported from the main frame at a point beneath the butt-removing mechanism. We have also shown a chute or guideway 16 leading from the butt-removing devices to

the husking devices and the rollers 14 coacting with the chute acting as a positive feed mechanism, whereby the ears of corn are delivered to the husking mechanism.

The husking mechanism, as here shown, 70 consists of a plurality of pairs of husking rollers, the rollers of each pair being operated in opposite directions so that they will pinch the husks between them and pull them from the ears. In the present instance, 75 we have employed two pairs of these rollers 17-18 and 19-20, respectively. The two central rollers or the inner roller of each pair, are journaled in plates 21 which are rigidly secured to and depend from the main 80 frame. The outer rollers are journaled in plates 22 which are pivotally connected at their upper ends to the opposite side members of the main frame and are resiliently connected at their lower ends to the plate 85 21; this connection preferably comprising in each instance a bolt 23 supporting a spring 26 confined between a lug 24 and nut 25. The tension of the spring tends to hold the outermost roller in contact with the innermost roller of each pair, but permits the rollers to move apart sufficiently to allow the husks to pass between the same. In this manner a strong gripping action is secured between the rollers without liability of choking the rollers with husks or other material 90 passing between them.

The husking rollers may, of course, be of any suitable construction, but in the construction here shown, in order to effectually 100 apply our present invention, one roller of each pair is preferably made of metal and is provided with spiral grooves 27 and 28, respectively. The opposite roller of each pair may be made of iron shafts covered 105 with rubber, as disclosed in our earlier invention referred to. However, in view of the improved rollers of the present invention these rollers may also be made of metal which is cheaper and more durable than the 110 rubber covered rollers.

The first pair of rollers comprising the rollers 17 and 18 are provided, respectively, with annular grooves 29 and oppositely disposed toothed disks or star wheels 30; the 115 spaces between the annular grooves on the roller 17 being traversed by sections of a spiral groove 27 and the spaces between the star wheels 30 on the roller 18 consisting of smooth portions 18a. It will be apparent 120 that the toothed disks will tear and loosen the husks on the ears of corn in such a manner as to enable the rollers to more readily grip and remove the same from the ears. The rollers 17 and 18 are further provided at one end with intermeshing toothed disks 31 which are adapted to engage the tips of the ears and tear the husks loose therefrom. The rollers are journaled in plates 21 and 22 and have arranged be- 130

tween the inner faces of the plates and the ends of the rollers collars 32.

The second pair of rollers 19 and 20 consist of the roller 19 which, as shown in the present construction, is formed of metal having a smooth cylindrical surface extending substantially the entire length thereof. The opposite roller 20 is also made of metal and has formed in the surface thereof and 10 extending the entire length of the roller the spiral 28. These rollers act to remove any portion of husks and silk from the ears of corn which may remain thereon after the ears have been operated on by the first pair 15 of rollers.

The spiral grooves 27 and 28 act to engage and carry off pieces of husks, cobs, butts or obstructive matter of any kind which may be upon the rollers incident to the husking 20 operations and serve to prevent such matter entering the bite of the rollers and obstructing or interfering with the proper functioning thereof. The spiral grooves act to carry off such obstructing matter as fast as 25 it may develop on the rollers. Thus, the rollers are kept clear and their proper operation is in no wise interfered with by such obstructing material. Movement may be imparted to the husking rollers in any suitable 30 manner. As shown in our earlier patent the shaft of each roller may extend beyond the supporting plate at one side of the machine, the projecting ends being provided with intermeshing gears and one of the 35 shafts, preferably the shaft which carries the roller 17, is provided with a sprocket wheel, about which extends a sprocket chain by means of which the rollers are actuated.

Suitable devices are arranged above the 40 husking rollers of each pair to engage the ears of corn and hold the same in engagement with the husking rollers and to rotate the ears while in engagement with the rollers. These devices preferably consist of 45 rotary brushes 33, one of which is supported above each pair of husking rollers and preferably having its axis arranged between the vertical planes of the axes of the two husking rollers constituting a pair. In 50 order that the rotary brushes may adapt themselves to ears of corn of varying size and may exert a uniform pressure thereon, they are so mounted as to be capable of limited vertical movement. This arrangement 55 also serves to cause the brushes to remove silk and loose husks from the ears more effectively. Any suitable mechanism may be employed for this purpose, a preferred form being disclosed and described in our patent 60 referred to herein.

Inasmuch as the ears of corn vary in length and all the ears have been moved to the opposite side of the machine in order that the butts may be removed therefrom, 65 it is desirable that means should be provided

for moving the ears toward those ends of the rollers having the toothed disks 31, thereby enabling these disks to engage the tip of the ears. Such mechanism may consist of two tapered rollers 34 and the means 70 for operating the same, as disclosed in our earlier construction. However, the improvements of the present invention make the use of the tapered rollers unnecessary as the spiral grooves of one roller of each 75 pair act to engage the husks of the ears of corn, thereby advancing the ears along the rollers into contact with the toothed disks 31.

Suitable means are also provided for removing the silk and bits of husk from the husking rollers. This means preferably comprises a plurality of rotary brushes 35, one for each roller, which may be operated by connecting the same to the operating 85 mechanism for the husking rollers or in any suitable manner.

It is, of course, obvious that the improved husking rollers provided with the spiral grooves will operate equally effectively 90 whether the ears of corn are moved transversely across the rollers, as in the construction here shown, or moved longitudinally of the rollers, as may be provided in a modified arrangement of the rollers and the feed- 95 ing mechanism therefor.

The endless feed belt which has conveyed the ears of corn through the butt removing mechanism, through the chute and across the husking rollers, also serves to deliver the 100 husked corn through a chute 36 into a receptacle or into a suitable conveyer as may be desired. The husks drop from the husking rollers onto an endless belt conveyer (not shown), disposed beneath the husking rollers 105 and are delivered thereby to a suitable distance from the machine. The butts severed from the ears by the cutter mechanism also fall upon this conveyer through a chute and are likewise disposed of.

The operation of the machine as a whole will be readily understood from the foregoing description of the several parts thereof and it will be apparent that the construction and arrangement of the several parts 115 is such that the ears of corn are, first, presented to the butting mechanism and after they have been acted upon by the butting mechanism are fed to the husking devices and are positively moved into a position to be 120 properly acted upon thereby; that the ears will be held in engagement with the husking rollers and rotated during the husking operation without bruising the grains of corn or injuring the ears; that the husking rollers 125 will maintain a strong, gripping action on the husks, but will move apart to permit the passage of the husks, thus avoiding the choking of the rollers with the husks; that the spiral grooves 130

of one of the husking rollers of each pair will act to engage and remove pieces of obstructing material of any kind which may be upon the rollers and thus prevent such material entering the bite of the rollers and interfering with the proper functioning thereof; and that the rollers and the husk-loosening devices will be freed from any husks or silk which may adhere thereto. It 10 will further be apparent that the machine as a whole is of a very compact arrangement and is simple in its construction and operation.

It will further be noted that the removal 15 of the butt of the ears of corn serves to loosen the husks thereon and thus facilitate the action of the husking mechanism when the ears have been fed to the latter.

While we have here shown one form of 20 our invention we wish it to be understood that this form is chosen for the purpose of illustration only, and we do not desire to be limited to the details of construction shown and described, for obvious modifications will 25 occur to a person skilled in the art.

Having thus fully described our invention, what we claim as new and desire to secure by Letters Patent, is:

1. In husking rollers, the combination, 30 with a plurality of pairs of rollers comprising a pair of rough husking rollers and a pair of finishing rollers coacting therewith, means to deliver ears of corn from one to the other of said rollers; one member of the 35 rough husking rollers being provided with a plurality of toothed devices spaced apart on said roller, and a toothed device secured to one end of said roller, the other member of the rough husking rollers being provided 40 with annular grooves corresponding in number to and coacting with said spaced toothed devices, the portion of the roller between said grooves being traversed by a spiral groove, and a toothed device secured 45 to one end of said roller and coacting with the toothed device secured to the end of the opposite roller; said finishing rollers being adapted to coact with the rough husking rollers to complete the husking of the corn.

50 2. In husking rollers, the combination, with a plurality of pairs of rollers comprising a pair of rough husking rollers and a pair of finishing rollers coacting therewith, means to deliver ears of corn from one to the other of said rollers; one member of the 55 rough husking rollers being provided with a plurality of toothed devices spaced apart on said roller, and a toothed device secured to one end of said roller, the other member 60 of the rough husking roller being provided with annular grooves corresponding in number to and coacting with said spaced toothed devices, a toothed device secured to one end of said roller and coacting with the toothed 65 device secured to the end of the opposite

70 roller, said finishing rollers coacting with the rough husking rollers to complete the husking of the corn and having a spiral groove in one member thereof to prevent lodgment of obstructive matter in the bite of said rollers.

3. In husking rollers, the combination, 75 with a plurality of pairs of rollers comprising a pair of rough husking rollers, one member of which is provided with a plurality of toothed devices spaced apart on said roller having a toothed member secured to one end of said roller, the other member of said pair of rollers being provided with annular grooves corresponding in number 80 to and coacting with said plurality of toothed devices, the portions of the roller between the annular grooves being traversed by a spiral groove and having secured to one end of said roller a toothed member coacting with the first-named toothed member, and a pair of finishing rollers coacting 85 with said first pair of rollers, one member of which is provided with a plain surface extending substantially the entire length 90 thereof, and the other member having a spiral groove therein acting to prevent obstructive matter lodging in the bite of the 95 rollers.

4. In husking rollers, a pair of rollers, 100 one member of which is provided with a plurality of toothed devices spaced apart on said roller and a toothed member secured to one end of said roller, the other member of said pair of rollers being provided with annular grooves corresponding in number 105 to and coacting with said plurality of toothed devices, the portions of the roller between the annular grooves being traversed by a spiral groove and having secured to one end of said roller a toothed member coacting with the first-named toothed member.

5. In husking rollers, a pair of rollers, 110 one member of which is provided with a plurality of toothed devices spaced apart on said rollers, the other member of said pair of rollers being provided with annular grooves corresponding in number to and coacting with said plurality of toothed devices, the portion of the roller between the 115 annular grooves being traversed by a spiral groove.

6. In a husking device, a pair of coacting rollers, one of said rollers being provided with toothed devices adapted to engage the 120 husks of ears of corn moving over said rollers; the other roller being provided with annular grooves coöperating with said toothed devices and having a spiral groove adapted to engage said husks, thereby acting 125 to move the ears of corn longitudinally of the rollers into engagement with the toothed devices and to prevent lodgment of obstructive matter in the bite of the rollers.

7. In a husking device, husking rolls con- 130

sisting of a plain surface roll and a roll provided with spiral grooves of substantial width extending entirely around the same and throughout its length, the width of the 5 surface of said roll between said grooves being greater than the width of said grooves and the surface between said grooves adapt-

ed to contact with said plain roll throughout the width of said surface.

In testimony whereof, we affix our sig- 10 natures.

SAMUEL E. MORRAL.
WILLIAM W. MORRAL.
